UNITED STATES PATENT OFFICE.

EDWIN N. KRAEMER, OF CEDARBURG, WISCONSIN.

VALVE-SPRING REMOVER.

1,147,804.

Specification of Letters Patent. Patented July 27, 1915.

Application filed December 8, 1914. Serial No. 875,211.

To all whom it may concern:

Be it known that I, EDWIN N. KRAEMER, a citizen of the United States, and resident of Cedarburg, in the county of Ozaukee and State of Wisconsin, have invented new and useful Improvements in Valve-Spring Removers, of which the following is a description, reference being had to the accompanying drawings, which are a part of this specification.

This invention has for its object to provide a valve spring remover constituting an improvement upon the construction covered by United States Letters Patent No. 1,935,974, dated August 20, 1912.

The object of the invention is to provide the valve spring remover with one jaw member having its parts forming the pair of projecting horns adjustable with relation to each other to accommodate between them valve stems of projecting valve guides of different diameters.

With the above and other objects in view the invention consists in the valve spring remover as herein claimed and all equivalents.

Referring to the accompanying drawing in which like characters of reference indicate the same parts in different views: Figure 1 is a view of a valve spring remover constructed in accordance with this invention, showing the manner of use thereof, parts of an engine being shown in section for this purpose. Fig. 2 is an enlarged detail view thereof showing the spring compressed between its jaws; Fig. 3 is a plan view thereof; Fig. 4 is an end view thereof; and, Fig. 5 is a view of the adjustable jaw member looking at its inner face and showing by dotted lines the adjustability thereof.

In these drawings the parts are for convenience designated by the same reference characters employed in the drawing of my former patent wherever possible.

The engine 8 with its exhaust valve 9 and cam 10, the valve stem 11, the cam rod 12, valve spring 13 and the valve casing 14, all being of ordinary construction and forming no part of the present invention, are shown as before to illustrate the manner of use of the valve spring remover. The valve casing 14, however, is shown with a depending lug or boss forming a valve stem guide 14' to show the necessity for the adjustable fea-

ture of one of the valve remover jaw members.

The tool itself comprises, as before, the levers 16 pivotally connected to the transverse member 17 with the pair of toggle links 20 connecting the levers to a threaded rod 21 passing through an opening 22 in the transverse member and having the thumb nut 23 threaded on its end for opening and closing the levers. The jaw member of one of the levers 16 remains as before, with the opening 18 in its end to receive the valve stem and the depression 19 to form a seat for the spring.

Instead of both jaw members being alike as before, the jaw member of the other lever 16 is adjustable. The enlarged end 25 of this lever 16 terminates in a straight edge at right angles to the longitudinal axis of the lever and is rabbeted on its inner surface to form a shouldered guideway or seat 26 for a pair of jaw blades 27 which are held in place thereon by means of a bolt 28 passing through the member 25 and through slots 29 in the jaw blades. The jaw blades 27 are preferably of sheet metal with their edges bearing against the shoulder of seat 26 so as to be guided thereby in their adjustments, and each having an outwardly projecting horn 30 with edges forming flanges 31 bent out of the plane thereof to form a seat for the valve spring. These flanges 31 taper to a wedge like shape to facilitate the introduction of the coil spring remover between the convolutions of the spring or between the end of the spring and the valve casing 14.

The objection to a coil spring remover with bifurcated jaw members on the ground that the members must be engaged with the spring beyond the end of the projecting valve rod guide or else the horns thereof will be too far apart to retain the valve springs of other engines is overcome by the adjustability of the jaw blades of this invention which enable them to be moved to position the horns 30 nearer together or farther apart, either to closely embrace the thinnest valve rod or to receive between them the largest valve rod guide. This enables the spring to be engaged near each end by the respective jaw members of the spring remover whether the valve rod is surrounded by a guide projection or not and consequently permits of a degree of compression.

of the spring which will in all cases relieve the cotter pin 15' from pressure so that it may be removed and the valve with its stem withdrawn, leaving the spring held between 5 the jaw members of the spring remover until it is desired to reassemble the parts.

The adjustability of one jaw member of the device is sufficient to adapt it for use generally with motors of various sizes and 10 makes so that the one tool is sufficient equipment for removing valve springs in general repair work.

What I claim as new and desire to secure by Letters Patent is:

15 1. A valve spring remover, comprising a pair of bifurcated jaw members, and means for moving the jaw members toward each other for compressing a spring between them; one of the jaw members comprising a 20 pair of horns adjustable with relation to each other.

2. A valve spring remover, comprising a pair of levers pivotally connected together, means for moving the levers toward or 25 away from each other, a forked jaw on one lever, there being a shouldered seat extending transversely across the inner face of the other lever, a pair of jaw blades fitting together on said seat, a bolt passing through

the end of said lever and through slots in 30 the jaw blades parallel with the shoulder of the seat, and horns projecting from the jaw blades to form together a forked jaw member with the horns adjustable with relation to each other.

3. A valve spring remover, comprising a pair of levers pivotally connected together, 35 means for moving the levers toward or away from each other, a forked jaw on one lever, there being a shouldered seat extending transversely across the inner face of the other lever, a pair of jaw blades fitting together on said seat, a bolt passing through the end of said lever and through slots in 40 the jaw blades parallel with the shoulder of the seat, horns projecting from the jaw blades to form together a forked jaw member with the horns adjustable with relation to each other, and tapering flanges bent up from the edges of the horns to form a spring 45 seat.

In testimony whereof, I affix my signature, in presence of two witnesses.

EDWIN N. KRAEMER.
